UNITED STATES PATENT OFFICE.

CHARLES A. HOTCHKISS, OF BRIDGEPORT, CONNECTICUT.

IMPROVEMENT IN CURRY-COMBS.

Specification forming part of Letters Patent No. 177,839, dated May 23, 1876; application filed March 15, 1876.

To all whom it may concern:

Be it known that I, CHAS. A. HOTCHKISS, of Bridgeport, in the county of Fairfield and State of Connecticut, have invented a new and valuable Improvement in Curry-Combs; and I do hereby declare that the following is a full, clear, and exact description of the construction and operation of the same, reference being had to the annexed drawings, making a part of this specification, and to the letters and figures of reference marked thereon.

Figures 1 and 2 of the drawings are perspective views of my curry-comb. Figs. 3, 4, 5, 6, and 7 are modifications of the same.

This invention relates to curry-combs; and it consists in the construction, by casting in one piece of metal, of a side handle, raised side bar, frame, and knockers, adapted for attachment to the back of a curry-comb, as herein-after described and claimed.

The letters B of the drawings represent the teeth-bars or body of a comb; C, the metallic side handle; b, a raised arched side bar; A, the side and end bars of the frame, and a the knockers.

For convenience in the process of casting, I prefer, when the handle is to be formed with a slotted or open center, that the opening shall be vertical, as shown on Fig. 1. I sometimes, however, prefer to cast such handles with a horizontal opening, as shown on Figs. 2 and 3.

The modifications illustrated by Figs. 2, 3, and 7 show rings or thumb-supports on the

rear end of their handles, while the modifications shown by the other figures represent this outer rest as wanting. I sometimes prefer to form a thumb-rest upon the end of my handle, adjoining the comb-frame. In place of a ring or other thumb-support, I sometimes construct my handle with a neck or shank, marked c on Fig. 5, and curve that end of the handle to a circular form, as shown at f on said figure. I sometimes also construct my handle with a ring at each end, as represented by Fig. 3, or with one ring and a segment, as shown on Fig. 2.

The raised and curved bar b serves to raise the handle to the proper height above the comb-back, and the knockers a enable the operator to clear the comb from its impurities.

I sometimes prefer to cast a tang upon my frame, to receive and hold a wooden handle. Such a modification is shown on Fig. 6 of the drawings.

What I claim as new, and desire to secure by Letters Patent, is—

In curry-combs, the handle C, raised bar b, frame A, and knockers a, all constructed in one piece of cast metal, substantially as described.

In testimony that I claim the above I have hereunto subscribed my name in the presence of two witnesses.

CHARLES A. HOTCHKISS.
